United States Patent Office

Des. 181,651
Patented Dec. 10, 1957

181,651

ANDIRON FRONT

Albert Montgomery Huntington, New Hartford, N. Y.,
assignor to Bennett-Ireland, Inc., Norwich, N. Y., a corporation of New York

Application October 5, 1956, Serial No. 43,247

Term of patent 14 years

(Cl. D81—6)

Fig. 1 is a perspective view of an andiron front showing my new design;

Fig. 2 is a front elevational view;

Fig. 3 is a side elevational view; and

Fig. 4 is a top plan view.

The rear face of the andiron front is substantially flat and unornamented.

I claim:

The ornamental design for an andiron front, as shown and described.
